(57) **CLAIM**

The ornamental design for a bottle, as shown and described.

DESCRIPTION

1. Bottle

1.1 is a front perspective view of a bottle showing my new design;

1.2 is a front elevation view thereof;

1.3 is a rear elevation view thereof;

1.4 is a left side elevation view thereof;

1.5 is a right side elevation view thereof;

1.6 is a top plan view thereof; and

1.7 is a bottom plan view thereof.

The dashed broken lines define the bounds of the claimed design and form no part of the claimed design.

The representations of the design are in black and white; the design does not claim protection for a specific coloring; the broken lines in the Figures of Design 3 and 4 show portions of the product which form no part of the claimed design.

1 Claim, 7 Drawing Sheets
